UNITED STATES PATENT OFFICE

GROVER C. HILTON, OF HUTCHINSON, KANSAS

DESIGN FOR A DISPLAY CASE

Application filed July 22, 1932. Serial No. 44,409. Term of patent 7 years.

To all whom it may concern:

Be it known that I, GROVER C. HILTON, a citizen of the United States of America, residing in Hutchinson, in the county of Reno and State of Kansas, have invented a new, original, and ornamental Design for a Display Case, of which the following is a specification, reference being had to the accompanying drawing, forming a part thereof.

The figure is a perspective view of a display case showing my new design.

I claim:

The ornamental design for a display case as shown.

GROVER C. HILTON.
